UNITED STATES PATENT OFFICE.

JOSEPH B. WOYTASSEK, OF GENESEO, NORTH DAKOTA.

GATE.

Application filed January 28, 1919. Serial No. 273,538.

To all whom it may concern:

Be it known that I, JOSEPH B. WOYTASSEK, a citizen of the United States, residing at Geneseo, in the county of Sargent and State 5 of North Dakota, have invented certain new and useful Improvements in Gates; and I do hereby declare the following to be a full, clear, and exact description of the invention, such as will enable others skilled in the art 10 to which it appertains to make and use the same.

This invention relates to gates, and the primary object of the invention is to provide an improved gate for moving-picture theaters and the like, which is so constructed 15 as to dispense with the services of the cashier and ticket taker.

Another object of the invention is to provide an improved gate for moving picture theaters and the like which is so constructed 20 that upon the depositing of the required coin, the gate may be operated so as to allow one person to enter the building.

A still further object of the invention is to 25 provide a gate for moving-picture theaters and the like of the turn-stile type, which is coin controlled so that persons may pass into the building upon depositing of the required coin.

30 A still further object of the invention is to provide an improved gate of the turn-stile type, which is held against rotation by means of a dog or the like, which is adapted to be swung out of operative position by means of 35 an apparatus controlled by a coin, said dog or other locking mechanism being held out of engagement with the gate by means of a lever, which engages the same while the gate is turning a predetermined sector of a circle.

40 A still further object of the invention is to provide an improved gate of turn-stile type and coin controlled which is so constructed that only one person can enter through the gate at a time.

45 A still further object of the invention is to provide an improved moving-picture house gate or the like which will be durable and efficient in use, one that is simple and easy to manufacture, and one that can be placed 50 upon the market at a reasonable cost.

With these and other objects in view, the invention consists in the novel construction, arrangement and formation of parts, as will be hereinafter more specifically described,

claimed and illustrated in the accompanying 55 drawings, forming a part thereof, in which:

Figure 1 is a perspective view of the improved gate.

Figure 2 is a central vertical longitudinal 60 section through the same.

Figure 3 is a front elevation of the same.

Figure 4 is a side elevation of the hollow supporting post, showing one wall thereof removed.

Figure 5 is a central vertical longitudinal 65 section through the post taken on the line 5—5 of Figure 3.

Figure 6 is a vertical section through the post taken at right angles to Figure 5 and on the line 6—6 of Figure 4.

Figure 7 is a detail horizontal section 70 taken on the line 7—7 of Figure 5.

Figure 8 is a detail horizontal section taken on the line 8—8 of Figure 5.

Figure 9 is a detail perspective view of the 75 coin pan, and the means for engaging the same to hold the pan in its lowered position and the dog for engaging the gate mechanism to hold the same against movement removed from the casing for clearness.

Figure 10 is a detail perspective view of the 80 cam for limiting the rotation of the gate.

Referring to the drawings in detail, wherein similar reference characters designate corresponding parts throughout the 85 several views, the numeral 1 generally indicates the improved gate which includes the platform 2, the hollow supporting post 3, in which is mounted the mechanism for controlling the movement of the arms 4 forming 90 a portion of the gate. A casing 5 is secured to the upper end of the post in which the arms are received.

The platform 2 includes a frame 6 having side walls 7 and the end walls 8 and 95 the upper wall 9, the central portion of which is removed and replaced by a pivoted plate 10, which has secured to the rear edge thereof a downwardly extending cleat 11, having pins 12 formed on the ends thereof 100 which are inserted through apertures in the side walls. A transverse cleat 13 is secured to the side walls in front of the depending cleat 11, and an expansion coil spring 14 is confined between the cleat and the transverse strip and normally tends to hold the opposite end of the plate 10 in elevated position. One of the side walls ad-

10 jacent to the free end of the pivoted plate is provided with an upwardly extending arcuate rod 15, which is received by an eye 16 carried by the plate 10. A coil spring 17 is wound around the rod 15 and engages the eye and normally holds the free end of the plate in its raised position. A strip 18 extends across the free end of the plate 10 and the terminals thereof are extended beyond the side edges of the plate and the side walls of the frame are recessed as at 19 to receive the same, when the plate is depressed. The post 3 includes a rear wall 21, the front wall 22 and the side walls 23 and 15 an upper wall 24. The post 3 is secured to one of the side walls 7 intermediate the ends thereof by any suitable means and the arms 4 are adapted to extend across the platform so as to form a barrier for preventing persons from entering into the theater or other place where the gate may be used. A hollow shaft 26 is mounted in suitable bearings 27 and 28 carried by the upper wall 24 and horizontal partitions 27', 20 respectively. The upper end of the shaft protrudes through the bearings of the upper wall 24 and the contour thereof is formed non-cylindrical in cross section and receives the gate 1 proper, which includes 25 the hub 29 and the radially extending arms 4, which, as shown, are four in number. It is to be understood, however, that any number of arms, provided the same are equidistantly spaced, may be provided. The 30 casing 5 is secured to the upper end of the post 3 as described above and constitutes upper and lower substantially semi-circular walls 30 and a semi-cylindrical side wall 31. The portion of the casing which faces 35 the platform is left open, so that the arms can ride out of the casing, when the same are actuated. The lower end of the hollow shaft 26 extends below the partition and has keyed or otherwise secured thereto a 40 relatively large gear wheel 32, which has meshing therewith a pinion 33, which is keyed to a vertical shaft 34 which is positioned at one side of the casing and has the terminals thereof journaled in the partition 45 27' and a horizontal strip 35. The shaft 34 has keyed thereto a relatively large gear wheel 36, which in turn meshes with a pinion 37 which is keyed to a shaft 38, the terminals of which are received in bearings 50 39 secured to the wall 22. The shaft 38 has keyed thereto a relatively large gear wheel 40 which is positioned below the strip 35 and this wheel is adapted to be engaged by a pawl 41, which will hereinafter be 55 more fully described, which holds the gear against movement and the shaft against rotation.

Pawl 41 includes a horizontal arm 42 having the inturned sharpened end or dog 60 43, which forms the means for engaging

the teeth of the gear wheel 40, and the vertical downwardly extending rod 44, which is rotatably secured as at 45 to the side wall of the casing and terminates in a horizontal inwardly extending arm 46, which is adapted to be actuated by the coin controlled mechanism 47. The coin controlled mechanism 47 includes a chute 48 which is positioned in the hollow shaft and extends below the same and terminates directly above 70 the pivoted coin pan 50. The chute extends above the outer surface of the casing 5 and terminates in a head 51, which is provided with a slot 52 which registers with the opening in the chute. The coin pan 50 80 is formed preferably of a single sheet of metal which is bent to form a pair of spaced side walls 53 which compress together at their rear ends as at 54 and are positioned between a pair of brackets 55 which are secured to the wall 21 of the post and the pan is secured to the bracket by means of a pivot pin 56. The pan is normally held in its raised position by means of a spring 57, which has the terminals 90 thereof connected to the rear end of the pan as at 57' and to the wall 21 of the casing. A loop 58 is secured to the coin pan 50 and receives the arm 46 of the pawl 41, and when the pan is in its raised position, the 95 dog is held into engagement with the teeth of gear wheel 40. The lower edge of the coin pan is bent to form a bow to rotatably receive the rod 59', the forward end of which has secured thereto the upwardly extending finger 61, and the rear end of the rod 59' is provided with a downwardly extending arcuate arm 59 and the lower end of the same is provided with a weight 60 which normally tends to hold the finger 61 100 in front of the open end of the pan so as to prevent the coin from rolling out of the pan, when the same is lowered by the weight of the coin. The arm is adapted to be engaged by the angular end 62 of an arm 63, 110 which is formed on the lower end of the vertical rod 64 which is rotatably secured as at 65 to the wall 22 and terminates at the upper end in a horizontally extending portion 66, which is normally held in inwardly extending position by means of the coil spring 67, which is secured thereto and to the wall 21 of the casing.

It can be seen that when a coin is dropped down the chute, the same will drop into the 120 pan 50 and the weight of the coin will overcome the tension of the coil spring 57 and thus extend the same, which will swing the rod 44 through the medium of the arm 46 and thus move the dog 43 out of engagement with the teeth of the wheel 40 and thus allow the shaft to be rotated.

It is essential to have some means for rotating the gate when a coin is deposited and a person desires to pass into the theater. 130

To accomplish this, a clutch member 68 including a section 69 is keyed or otherwise secured to the shaft 26 and a sliding section 70 is normally held out of engagement with the sections 69 by means of an expansion coil spring 71. A cam shaped member 72 is secured to the clutch section 70 and the periphery of the same is provided with a groove 73 in which is fitted a cable 74, which has one end thereof secured to the device as at 75 and the opposite end of the cable is extended through an opening 76 and is secured to a loop 77 which is pivotally connected as at 78 to a rod 79 which extends into a casing 80. A spring 81 is coiled around the rod and bears against a shoulder 82 formed on the lower end thereof and the upper wall of the casing. The lower end of the casing is provided with a pair of spaced ears 84, which are positioned on each side of a lever 85, and are pivotally connected to the same by means of a pin 86. The lever 85 extends through a slot 87 in the wall 21 and extends transversely across the casing and is pivoted to the opposite wall 22 by means of a pin 87' and is extended through the wall 22. The lever 85 is normally held in raised position by means of the coil spring 88, which is pivotally connected to end of the lever which is extended through the wall 22. The lever 85 is provided with a plurality of transverse apertures 89, in any one of which is adapted to be fitted the eye 90, which receives the hook 91 carried by the extended terminal of the transverse strip 18. Thus it will be seen that when the platform is lowered by the weight of a person, the lever 85 is drawn down against the tension of the coil spring 88, which in turn draws the casing 80 downward and pulls the cable 74, which lowers the section 70 of the clutch 68 into engagement with the clutch section 69 and upon further downward movement of the lever and platform, the spring 81 and the casing 80 are slid downward on the rod 79, which tends to draw the cable downward and rotate the shaft, when the coin pan is tripped.

Upstanding posts 94 are rigidly secured to the platform opposite the gate and have secured thereto at the upper ends thereof the railing 95 which necessitates the persons desiring to enter the theater to step upon the platform.

In operation of the improved gate, a person desiring to enter into the theater or other place in which the gate is used, steps upon the pivoted portion of the platform 10 and lowers the same which, as above stated, will lower the clutch section 70 into engagement with the clutch section 69 and a coin of the desired denomination is then deposited in the chute 48, and the coin falls into the pan 50 and lowers the same, which brings the toothed end of the pawl out of

engagement with the gear wheel 40 and allows the gate to be turned by the weight of the person on the platform. As soon as the pawl comes out of engagement with the gear wheel 40, the coil spring 81 which has been compressed by the platform pulls the cable 74 and rotates the cam 72, one-quarter of a revolution, which also turns the shaft and gate. Further movement of the cam is prevented owing to the enlarged portion of the same engaging the wall of the casing and thus further movement of the gate is prevented. This prevents more than one person entering into the theater at a time. The lower clutch section 69 is provided at spaced points with teeth 92 and when the shaft has been rotated substantially one-quarter of a revolution by the coil spring 81, one of the teeth comes into contact with the arm 66 of the rod 64 and swings the same on its bearing and thus moves the lower arm 63 into engagement with the depending arm 59 and rotates the rod 59' in the barrel formed on the pan and swings the finger 61 away from the front of the pan and allows the coin to roll therefrom and into the coin box 95 which is slidably mounted in the hollow post 3 directly below the coin pan 50. As soon as the person steps off of the platform, the clutch section 70 is returned to its normal position by the coil spring 71. As soon as the gate has turned the quarter of a revolution the arm 66 slides out of engagement with one of the teeth 92 and thus is returned to its normal position by means of spring 67, which throws the lower arm 63 out of engagement with the depending arm 59 and the pan 50 is returned to its normal position under the influence of spring 57 and allows the pawl 43 to engage the gear wheel 40 and thus hold the gate against further movement until another person steps on the platform and deposits a coin.

From the foregoing description it can be seen that an improved turn-stile gate is provided which is coin controlled, and is especially adapted for moving-picture theaters and will effectively prevent more than one person entering the theater at a time. While the gate has been described as being specially adapted for moving-picture theaters and the like, it is to be understood that the same can be used for any other purpose that may be desired, as for instance on street cars of the pay-as-you-enter type.

In practice, I have found that the form of my invention illustrated in the accompanying drawings and referred to in the above description, as the preferred embodiment, is the most efficient and practical; yet realizing the conditions concurrent with the adoption of my device will necessarily vary, I desire to emphasize that various minor changes in details of construction, proportion and ar-

angement of parts may be resorted to, when required without sacrificing any of the advantages of my invention as set forth.

What I claim as new is:

5. 1. In a device of the class described, a turnstile gate, a hollow rotatable shaft carried by the gate, a pivoted coin pan positioned below the hollow shaft, spring means normally holding the coin pan in a raised position, a relatively large gear wheel carried by the lower end of the shaft, a train of gear wheels operatively connected with and extending below the first mentioned gear wheel, a pivoted dog engaging one of the 15 gear wheels to hold the same against movement, means operatively connecting the coin pan with the dog, teeth carried by the shaft, and a pivoted arm arranged in the path of the teeth, and an inwardly extending extension formed on said arm for engaging said 20 coin pan.
2. In a device of the class described, a turn-stile gate, a hollow rotatable shaft carried by the gate, a coin pan pivoted beneath 25 said hollow shaft, means normally holding the coin pan in one position, a gear wheel carried by said shaft, a train of gear wheels operatively connected with and extending below the first mentioned gear wheel, means 30 engaging one of said gear wheels to retain the same against movement, means operatively connecting the last mentioned means with said coin pan, means to release the gear wheel holding means, at times, said coin pan being held in its operated position by the 35 weight of the coin therein during a quarter revolution of the turn-stile.
3. In a device of the class described, a turn-stile gate, a hollow rotatable shaft carried by the gate, a coin pan pivoted beneath 40 said hollow shaft and normally retained in horizontal position, said coin pan having an open end, means for engagement with the open end of said coin pan when the latter is 45 in horizontal position, said last mentioned means being adapted to be moved away from the open end of the coin pan at the end of the quarter revolution of the turn-stile, means to permit movement of the gate

a predetermined distance upon lowering of 50 the coin pan, means tending to rotate said shaft, and means for retaining said shaft against rotation when said coin pan is in horizontal position.

4. In a device of the class described, a turn- 55 stile gate, a hollow rotatable shaft carried by said gate, a pivoted coin pan positioned below said hollow shaft, a coin tube extended vertically through said shaft to direct coins to said coin pan, spring means nor- 60 mally holding the coin pan in a raised position, said gate being retained against opera- 65 tion when said coin pan is in raised position, means for rotating said shaft to operate said gate when said coin pan moves downwardly 70 with the weight of the coin directed thereto- by the coin tube, closing means for the end of said coin tube, said closing means being normally engaged against an open end of 75 said pan, and means for moving said closing means away from the open end of the coin pan at the end of the quarter revolution of the turn stile.

5. In a device of the class described, a turn-stile gate, a hollow rotatable shaft carried by said gate, a post for supporting and enclosing said shaft, a coin pan pivoted in said post beneath said shaft, a coin conduct- 80 ing tube extended vertically through said hollow shaft, to deposit a coin in said coin 85 pan, means for operating said gate, means for retaining the last mentioned means in inoperative position, a platform having a hinged portion adapted to be pressed down- 90 wardly to move the gate operating means into operative position, means for releasing the gate operating means when the coin pan is moved downwardly by a coin deposited therein, and means for releasing the coin from one end of the coin pan, said coin pan 95 being retained in its lowered position by the weight of the coin therein.

In testimony whereof I affix my signature in presence of two witnesses.

JOSEPH B. WOYTASSEK.
